DISPLAY STAND FOR YARN OR THE LIKE

Hans T. Oien, 2030 Wilson Ave.,
St. Paul, Minn. 55119

Filed Nov. 28, 1966, Ser. No. 4,822

Term of patent 7 years

(Cl. D80—9)

FIG. 1 is an elevational view of a display stand for yarn or the like showing my new design;

FIG. 2 is a top plan view thereof; and

FIG. 3 is a bottom plan view thereof.

I claim:

The ornamental design for a display stand for yarn or the like, as shown.
